(57)

CLAIM

The ornamental design for a “storage device,” as shown and described.

DESCRIPTION

FIG. 1 is a top rear left perspective view of a storage device, showing our new design;

FIG. 2 is a top view thereof;

FIG. 3 is a bottom view thereof;

FIG. 4 is a left-side view thereof;

FIG. 5 is a right-side view thereof;

FIG. 6 is a rear view thereof; and,

FIG. 7 is a front view.

The features shown in broken lines illustrate portions of the storage device and form no part of the claimed design.
